BURIAL VAULT COVER

Wesley M. Chandler and Paul F. Heuser, both of St. Paul, Minn., assignors to Wilbert W. Haase Co., Broadview, Ill., a corporation of Illinois

Filed Sept. 24, 1964, Ser. No. 31,865

Term of patent 14 years

(Cl. D19—1)

FIG. 1 is a perspective view of a burial vault cover, embodying our new design;

FIG. 2 is a top plan view thereof;

FIG. 3 is a side elevational view; and

FIG. 4 is an end elevational view.

We claim:

The ornamental design for a burial vault cover substantially as shown.
